UNITED STATES PATENT OFFICE.

BENJAMIN LEVENE, OF NEW YORK, N. Y.

DESIGN FOR VASES.

Specification forming part of Design No. 6,021, dated August 13, 1872.

To all whom it may concern:

Be it known that I, BENJAMIN LEVENE, of No. 176 Bowery, New York, in the county and State of New York, have invented a new and useful Design for Vases, of which the following is a specification:

The nature of my design is fully represented in the accompanying illustration; and my said design consists more particularly in the novel conformation of the bowl of the vase, which renders the manufacture of easy execution and imparts a new and fresh beauty to ornamental vases, thereby producing an article of manufacture combining the advantages of facility of structure, and of affording that relief which the lover of art finds in unique and pleasing configurations.

The accompanying illustration represents an elevation of a design for a vase having a novel shape and configuration.

The vase is of blown glass, and I have been manufacturing them to imitate stone, china, earthenware, &c., and adorning them with va-

rious devices, and have put them upon the market under the style of "Potichomania Vases."

In the design shown it will be seen that the outlines of bowl emanate from the pedestal in almost angular lines, when, after being produced outward the proper distance, an almost abrupt curve continues them to the neck of the vase, and thus do I produce a vase which, in its nature as a design, produces a most pleasing effect upon both the eye and the mind of the observer.

Having described my invention, I claim—

The vase, of the design and configuration herein described, and shown in the accompanying illustration.

In testimony whereof I have hereto set my hand this 1st day of July, A. D. 1872.

BENJAMIN LEVENE.
